United States Patent Office

Des. 211,876
Patented Aug. 6, 1968

211,876

COMBINED BATH TUB AND GRAB RAILS

Donald W. Doman, Janesville, Wis., assignor to Kohler
Co., Kohler, Wis., a corporation of Wisconsin

Filed Feb. 20, 1968, Ser. No. 10,646

Term of patent 14 years

(Cl. D23—55)

Fig. 3

Fig. 4

FIG. 1 is a perspective view of a combined bath tub and grab rails showing my new design;

FIG. 2 is a top plan view thereof;

FIG. 3 is a cross sectional view taken on line 3-3 of FIG. 2; and

FIG. 4 is a cross sectional view taken on line 4-4 of FIG. 2.

The dominant features of the design reside in the portions shown in full lines.

I claim:

The ornamental design for a combined bath tub and grab rails, substantially as shown and described.
